UNITED STATES PATENT OFFICE.

GEORGE J. MUNSCHY, OF NEW YORK, N. Y.

BOTTLE ATTACHMENT.

1,154,535.

Specification of Letters Patent. Patented Sept. 21, 1915.

Application filed July 22, 1914. Serial No. 852,514.

To all whom it may concern:

Be it known that I, GEORGE J. MUNSCHY, a citizen of the United States, residing at New York, in the county of New York and State of New York, have invented new and useful Improvements in Bottle Attachments, of which the following is a specification.

This invention contemplates the provision of a bottle attachment primarily intended for use in connection with poison bottles whereby the stopper is wholly inclosed and locked in position, so that bottles of this character may be readily distinguished in the dark from other bottles, and to direct attention to the fact that the contents thereof are of a poisonous nature.

To this end the invention essentially consists of the provision of a cap comprising hinged sections to facilitate its application to and removal from the neck of the bottle, together with a novel construction of means for locking the sections associated.

Another object of the invention is the provision of a device of this character which is extremely simple in construction with a view of reducing the cost of manufacture of the same to a minimum.

In the drawing forming a part of this application like numerals of reference indicate similar parts in the several views, and in which:

Figure 1 is a view of the device applied to a bottle, Fig. 2 is a perspective view of the device, and Fig. 3 is a detail view of the latch.

Referring more particularly to the drawing 5 designates a bottle of the usual construction having a reduced neck portion 6 and enlarged mouth portion 7, the latter being closed by means of a stopper 8.

The attachment forming the subject matter of my invention comprises a cap *a* consisting of two similarly constructed sections 10 having the adjacent edges of the top portions 11 thereof hingedly connected together in any suitable manner. Each of the sections 10 have their intermediate portions bulged outwardly as at 12 to form an annular pocket when the sections are associated for the reception of the mouth 7 of the bottle, the lower portions 13 of the sections being reduced so as to snugly embrace the neck 6 of the bottle in applied position.

With a view of preventing casual separa-

tion of the cap from the bottle I employ a latch element 14 carried by the lower portion of one of the sections 10 and adapted to be received by the keeper 15 secured to the other of said sections. As shown in this particular instance, the latch element 14 is constructed from a single length of resilient material into U-form, the limbs 16 of which are held normally spaced through the medium of a leaf spring 17 interposed therebetween. The keeper 15 is also constructed from a single strip of material and comprises an offset central portion 18 having an instruck opening providing the spurs or projections 19 which engage with the slots 20 formed in the limbs 16 of the latch element, when the latter enters the keeper 15. When the parts are thus associated the cap will be effectively locked in position on the neck of the bottle and wholly inclose the stopper therefor. To remove the cap it is only necessary to press the limbs 16 toward each other whereupon the element 14 may be readily and easily withdrawn from the keeper and the sections 10 separated.

Manifestly with the cap in position the bottle can be readily distinguished in the dark from other bottles so as to prevent its contents from being inadvertently administered for medicines.

It is desired to be understood that I do not limit myself to the detailed construction of what I consider the preferred form of my invention as hereinabove described, and that various changes in the construction and form may be resorted to to accommodate the device to the different type bottles.

It is believed from the foregoing description that the nature and advantages of the invention will be clearly apparent without requiring a more extended explanation and therefore the same has been omitted.

What I claim is:—

In a bottle attachment, a cap comprising hingedly connected sections adapted to be placed over the mouth of the bottle and embrace the neck portion thereof, a substantially U-shaped keeper terminally secured to the exterior of one of the sections adjacent its meeting edge, a latch constructed from a single length of material into substantially U-form, one of the limbs of said latch being secured to the other section and projecting beyond the meeting edge thereof, a spring interposed between the limbs for

yieldably supporting the other of said limbs, and a projection extending inwardly from said keeper for interchangeable engagement with a series of apertures in the 5 said yieldably supported limb when the sections are operatively associated.

In testimony whereof I affix my signature in presence of two witnesses.

GEORGE J. MUNSCHY.
